CENTRIFUGAL BREATHER

Roland Chilton, Ridgewood, N. J., assignor, by
mesne assignments, to Wright Aeronautical
Corporation, Paterson, N. J., a corporation of
New York

Application April 8, 1936, Serial No. 73,191

13 Claims. (Cl. 123—196)

This invention relates to breathing and lubricant scavenging for engine crankcases, and comprises means correlating these two functions, whereby the normal breathing action is caused to assist scavenging of excess oil from the crankcase. The invention is particularly applicable to internal combustion engines of the dry sump type, wherein oil is fed to the parts requiring lubrication in excessive quantities, and wherein the excess oil is withdrawn by a pump and delivered to a separate oil tank. In such engines it has been normal practice to employ a vent or breather open to the atmosphere to relieve from the crankcase gases which collect therein as a result of escape past the engine pistons. Difficulty has been experienced in effecting a thorough separation of gas from oil atomized by the rapidly moving engine parts, which normally whip the oil into a fine mist or froth, this mist having a density not widely different from that of the crankcase gases. Engines are usually provided with a sump into which excess oil drains for scavenging, but ordinarily, a substantial amount of oil is lost through the breather despite breather location, and baffles or screens which may be associated therewith to prevent oil loss. Even when the breather is located in a high and relatively quiet and non-turbulent part of the crankcase, there is a substantial oil loss therethrough resulting in oil deposition on the outside of the engine with consequent dirtiness and undue oil consumption. If ventilation is resorted to wherein the oil carrying mist is diverted to the engine intake, undue oil consumption may result. It is an object of this invention to overcome these difficulties by providing a breathing passage so arranged with respect to the oil sump and oil tank that most of the atomized oil is given an opportunity to settle out in relatively quiet locations, and additionally, to provide a centrifugal separator to remove oil particles from crankcase gases. A further object is to augment the scavenging of oil from a crankcase by utilizing the common tendency for the oil mist to pass toward a breather opening, in locating the breather opening for the crankcase adjacent the oil sump. This reduces the normal diffusion of the oil carrying crankcase vapors, concentrating them at locations where separation of the oil may be affected by gravity, or by a centrifuge, or by both.

I have chosen for an illustrative embodiment of the invention, the crankcase of a radial cylinder aircraft engine, shown in the annexed drawings, in which:

Fig. 1 is a fragmentary view through an engine crankcase embodying the invention; and

Fig. 2 is an enlarged view of a portion of Fig. 1.

A main crankcase section 10 is provided with a front section 12 defining a forward compartment 5 and a rear section 14 defining a rear compartment. The various cylinders and parts subject to motion are not shown since they form no part of the invention. Suffice it to say, however, that the front, central and rear compartments, in engine operation, are filled with oil spray and mist, and that a certain amount of gas enters the compartments from the engine cylinders which must be disposed of by a breather opening. At the lower part of the end partitions of the section 15 10, openings 16 and 18 are provided to permit of compartment intercommunication. Thus oil may flow from any compartment through connections 20 and 22 to an oil sump 24 carried by said connections. 20

I form a breather opening 26 in the sump 24, forming the entrance to a conduit 28 entering the top of an oil reservoir 30. From a remote point on the top of the oil reservoir, a conduit 32 extends, which continues the breather passage 25 and provides a vent for the oil tank. The structure thus far described in itself, comprises a substantial part of the invention. In operation oil laden crankcase gases will seek an outlet which necessarily is the opening 26. A substantial amount of oil particles will deposit in the sump, the flow of gases also augmenting the passage of larger particles of oil to the sump, whence the oil is delivered by a conventional scavenge pump 33, from the outlet 34 to the oil tank 30 by a pipe 35. The vapors pass through the conduit 28 to the tank 30, where more of the oil particles may settle, directly into the oil in the tank. The vent 32 then communicates with the atmosphere. 40

To provide for conditions where excessive turbulence in the crankcase has made the above described arrangement inadequate to effect complete separation of oil from the crankcase gas, I provide a centrifuge shown in detail in Fig. 2. This comprises a high speed engine driven shaft 45 36 journaled in upper part of the section 12. The driving means is not shown but conveniently comprises a conventional gear train. A member 38 fits over the shaft 36, forming a housing for an impeller 40 mounted on the shaft 36. The housing is formed with an eye portion 42 concentric with the impeller, communicating with an opening 44 to which the conduit 32 is connected. A drain opening 46, in the housing 38 and section 12, leads from a point adjacent the impeller pe- 50 55

periphery to the front compartment within the section 12. A baffle 48 overlies the outer part of the impeller 40. Gases and oil particles entering the eye 42 are separated as they are picked up by the rotating impeller 40, the oil being thrown 5 against the housing 38 and the gases passing radially inward to issue from the baffle aperture 50 due to the low density of the gases alone.

I provide an outer housing 52 having a vent 10 opening 54, the housing 52, with the baffle 48 and the housing 38 being attached to the section 12 by studs 56.

A second impeller 58 may, if desired, be mounted 15 on the shaft 36 on the outlet side of the baffle 48, to augment gas passage through the centrifuge and to prevent a pressure drop thereacross, or to prevent a positive pressure being built up in the crankcase by the first impeller 40.

While I have described my invention in detail 20 in its present preferred embodiment, it will be obvious to those skilled in the art, after understanding my invention, that various changes and modifications may be made therein without departing from the spirit or scope thereof. I aim 25 in the appended claims to cover all such modifications and changes.

What is claimed is:

1. The combination with an engine crankcase having an oil sump and drainage passages for 30 scavenging oil from said case into said sump, of a conduit terminating in an atmospheric vent connected to said sump, a centrifuge in said conduit adapted to separate oil particles from issuing vapor, and means to drain said separated oil back into the crankcase.

2. In an engine, in combination, a crankcase to be vented of vapors and scavenged of oil, an atmospheric vent conduit connected to said crankcase through which said vapors and oil pass, a high speed impeller within said conduit adapted 40 to centrifugally separate said oil from said vapor, and a connection whereby said separated oil is returned to said engine.

3. In an engine, in combination, a crankcase to be vented of vapors and scavenged of oil, and 45 having a scavenge passage, a tank into which scavenged oil flows an atmospheric vent conduit connecting to said tank at a point thereon remote from said engine, an oil and vapor separating centrifuge in said conduit, and means to drain centrifuged oil back into said engine.

4. The combination with an engine, of an oil 50 sump, an external oil tank, a first vent pipe connecting said sump to said oil tank, a second vent pipe connecting said oil tank remotely of the first said pipe to an atmospheric vent, and oil separating means interposed in said second connection.

5. The combination of an engine crankcase 55 having a sump, of an oil tank, a scavenging conduit from said sump to said tank, a conduit from the interior of said crankcase to the upper part of said tank forming the sole vent for said crankcase, a vent pipe for said tank, and an oil separating centrifuge in said vent pipe.

6. The combination of an engine crankcase having a sump, of an oil tank, a scavenging conduit from said sump to said tank, a conduit from the interior of said crankcase to the upper part of said tank forming the sole vent for said crankcase, a vent for said tank and an oil separating centrifuge in said tank vent.

7. The combination of an engine crankcase having an oil collecting sump connected there- 75 below, of means to scavenge oil from said sump,

an engine driven centrifuge, a conduit from the upper part of said sump to the inlet side of said centrifuge, an oil return lead from the periphery of said centrifuge to the engine, and a vent at the outlet of said centrifuge.

8. The combination with an engine crankcase, of an oil sump having a relatively restricted connection with said crankcase and through which connection oil flows from the crankcase to the sump, an oil tank, means for discharging liquid 10 oil from said sump to said tank, a vent conduit directly connecting said sump and tank, entering both said sump and tank at points above the normal liquid oil level thereof, and means for promoting vapor flow from said engine, through 15 said vent conduit to said tank, comprising a blower organized to withdraw vapor from the tank.

9. In an engine casing containing oil vapor, a 20 vent system for said casing comprising a high speed impeller communicating at its eye with the interior of said casing, an oil collecting annulus encircling the impeller, said annulus communicating with the casing interior for the return of collected oil to said casing, an air vent 25 on the opposite side of said impeller from said eye, and a booster impeller rotatable with the first impeller for discharging casing gases from said vent.

10. In combination, an engine crankcase having an oil sump connected therebelow, means to scavenge oil from said sump, an engine driven centrifuge adapted to separate oil from vapor; a vapor conducting conduit leading from the upper part of said oil sump, above the normal liquid 35 oil level, to the centrifuge intake; a duct leading from the centrifuge for discharging oil separated thereby into the engine crankcase, and a discharge duct on the centrifuge for gases from which oil has been separated.

11. In an internal combustion engine provided with a lubricating system wherein lubricant is delivered to the engine case, an oil sump below and having restricted communication with the case into which surplus liquid oil flows, an oil tank separate from the engine, means for scavenging liquid oil from said sump and delivering same to said tank; a sole vent conduit for said engine directly connecting the upper part of said sump and the upper part of said tank, above the 50 normal liquid oil level of both, wherefore crankcase gases and vapor under pressure within the case due to explosion leakage from the engine pass into said sump to promote liquid oil flow thereto before passing from the engine; and a breathing vent for said tank.

12. In an internal combustion engine provided with a lubricating system wherein lubricant is delivered to the engine case, an oil sump below and having restricted communication with the case into which surplus liquid oil flows, an oil tank separate from the engine, means for scavenging liquid oil from said sump and delivering same to said tank; a sole vent conduit for said engine directly connecting the upper part of said sump and the upper part of said tank, above the normal liquid oil level of both, wherefore crankcase gases and vapor under pressure within the case due to explosion leakage from the engine pass into said sump to promote liquid oil flow thereto 65 before passing from the engine; and means to promote the exhaust of crankcase gases from the tank, which enter the tank from the engine case and sump.

13. In an internal combustion engine provided

with a lubricating system wherein lubricant is delivered to the engine case, an oil sump below and having restricted communication with the case into which surplus liquid oil flows, an oil tank separate from the engine, means for scavenging liquid oil from said sump and delivering same to said tank, a sole vent conduit for said engine directly connecting the upper part of said sump and the upper part of said tank, above the

5 normal liquid oil level of both, wherefore crank-

case gases and vapor under pressure within the case due to explosion leakage from the engine pass into said sump to promote liquid oil flow thereto before passing from the engine; and breathing means for said tank comprising a device for separating residual oil particles from issuing vapor organized to discharge gases to the atmosphere and to return oil particles to the lubricating system.

5
